US00D870078S

(12) **United States Design Patent** (10) **Patent No.:** **US D870,078 S**
Kim (45) **Date of Patent:** **** Dec. 17, 2019**

(54) **REMOTE CONTROLLER FOR DIGITAL
AUDIO PLAYER**

(71) Applicant: **CLARION CO., LTD.**, Saitama (JP)

(72) Inventor: **Jinbeom Kim**, Saitama (JP)

(73) Assignee: **CLARION CO., LTD.**, Saitama (JP)

(**) Term: **15 Years**

(21) Appl. No.: **29/646,199**

(22) Filed: **May 2, 2018**

(30) **Foreign Application Priority Data**

Nov. 29, 2017 (JP) 2017-026559

(51) **LOC (12) Cl.** **14-03**

(52) **U.S. Cl.**

USPC **D14/218**

(57) **CLAIM**

The ornamental design for a remote controller for digital audio player, as shown and described.

DESCRIPTION

FIG. 1 is a perspective view of a remote controller for digital audio player showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

1 Claim, 7 Drawing Sheets
